LOUIS C. W. MITCHELL AND JOHN A. FRETZ, OF PHILADELPHIA, PENNSYLVANIA, ASSIGNORS
OF ONE-THIRD TO EDWARD J. MITCHELL, OF PHILADELPHIA, PENNSYLVANIA.

TROLLEY.

No. 884,750.

Specification of Letters Patent.

Patented April 14, 1908.

Application filed March 27, 1906. Serial No. 308,213.

To all whom it may concern:

Be it known that we, LOUIS C. W. MITCHELL and JOHN A. FRETZ, citizens of the United States, residing at Philadelphia, county of 5 Philadelphia, and State of Pennsylvania, have invented a certain new and useful Improvement in Trolleys, of which the following is a specification.

Our invention relates to a new and useful 10 improvement in trolleys, and has for its object to provide an exceedingly simple and effective construction by which the trolley wheel will be caused to automatically assume the proper angle to follow the wire when 15 turning curves and so adjust itself as to come into alinement with the wire when the curve is passed.

With these ends in view, this invention 20 consists in the details of construction and combination of elements hereinafter set forth and then specifically designated by the claims.

In order that those skilled in the art to 25 which this invention appertains may understand how to make and use the same, the construction and operation will now be described in detail, referring to the accompanying drawing forming a part of this specification, in which—

Figure 1 is a side elevation of a trolley 30 made in accordance with our improvement. Fig. 2, a broken away section showing the arrangement of the swivel connections between the pole and trolley harp. Fig. 3, a plan view of the base of the swivel, the lugs de- 35 pending from the cap being in section.

In carrying out our invention as here embodied A represents the trolley pole, upon the upper end of which is mounted the base B, having formed therein the annular groove C 40 for the reception of the coil springs D. This base also has formed therein the annular groove E for the reception of the balls F.

The harp designated G, has at its lower end a cap H, formed with a downwardly projecting annular skirt or flange having its under- 45 face grooved to register with the annular groove C. This flange terminates in an annular depending rim portion which surrounds the edge portion of the base B, as a dust 50 guard and also to more effectively center the harp upon said base. In such relation of the parts ball bearings F, are provided which

seat in the groove E, and also in a groove in the underface of the cap H registering with the groove E.

The cap is held in place by the hollow stud I which is threaded into the base, having a head thereon for properly retaining the cap. The cap also has formed therewith the depending lugs J which project down into the 60 groove C between the ends of the springs D, here shown as four in number, the opposite ends of said springs being confined by the lugs K projecting upward from the bottom of the groove C.

Hollow pole A, terminates at a point below the top portion of the bore of base B, to thereby enable the hollow stud I, to be threaded into the upper part of the bore of base B. As depicted in Fig. 2, stud I, has a 70 hollow head which projects outwardly and by virtue of its engagement with the wall surrounding the opening provided for stud I, in cap H, retains the latter in relative position to base B. By this arrangement it will 75 be seen that the springs D being under tension will normally hold the harp and wheel journaled therein in alinement with the pole, but when the trolley is traveling around a curve the harp will swing upon the base after 80 the manner of a caster, thus following the wire without undue binding thereon, and as soon as the wheel has passed the curve it will automatically right itself, again coming into alinement with the pole. This is facilitated 85 by the harp being set at an angle to the axis of the cap, as will be readily understood.

The base and stud have central openings therethrough for the passage of the wire for conveying the current from the trolley to 90 the car.

Having thus fully described our invention, what we claim as new and useful, is—

In combination, a trolley pole, an annular base member secured to the upper end thereof 95 and formed with an annularly grooved projecting portion having webs at opposite points in the groove, a trolley harp formed at its lower end with a cap having a projecting portion formed with an annular 100 groove registering with the first named groove, lugs formed at opposite points in the second groove, expansive coil springs confined between the lugs and the webs, the

annular projecting portion of the cap terminating in an annular depending rim portion surrounding the annular edge portion of the base member and serving as a dust guard, and means for connecting the base member and the harp to allow of axial pivoted movement of the latter.

In testimony whereof, we have hereunto

affixed our signatures in the presence of two subscribing witnesses.

LOUIS C. W. MITCHELL.
JOHN A. FRETZ.
